UNITED STATES PATENT OFFICE

153,272

DESIGN FOR AN AVIARY PERCH

Peter C. Forner, Beltsville, Md., assignor of one-half to Raymond B. Taylor, Washington, D. C.

Application January 6, 1947, Serial No. 135,972

Term of patent 7 years

(Cl. D31—2)

To all whom it may concern:

Be it known that I, Peter C. Forner, a citizen of the United States, residing at Beltsville, in the county of Prince Georges and State of Maryland, have invented a new, original, and ornamental Design for an Aviary Perch, of which the following is a specification, reference being had to the accompanying drawing, forming part thereof.

Figure 1 is a perspective view looking at one side of an aviary perch embodying my new design; and

Figure 2 is a perspective view showing the opposite side.

I claim:

The ornamental design for an aviary perch, substantially as shown.

PETER C. FORNER.
